[57] CLAIM

The ornamental design for a souvenir hat, as shown and described.

DESCRIPTION

FIG. 1 is a right side elevational view of a souvenir hat showing our new design, the left side is a mirror image; FIG. 2 is a top plan view of the first embodiment; FIG. 3 is a bottom plan view of the first embodiment; FIG. 4 is a rear elevational view of the first embodiment; FIG. 5 is a front elevational view of the first embodiment; FIG. 6 is a right side elevational view of a second embodiment of a souvenir hat showing our new design, the left side is a mirror image;

FIG. 7 is a top plan view of the second embodiment; FIG. 8 is a bottom plan view of the second embodiment also illustrating the recess for receiving the head of a wearer and the slits defined on opposite sides of the recess for accommodating various head sizes;

FIG. 9 is a rear elevational view of the second embodiment; FIG. 10 is a front elevational view of the second embodiment; and,

FIG. 11 is a front elevational view of the second embodiment, the broken line showing of the human form is for illustrative purposes only and forms no part of the claimed design.
